UNITED STATES PATENT OFFICE

160,993

PAPER NAPKIN

Wilbur J. Boucher, Green Bay, Wis., assignor to Fort Howard Paper Company, Green Bay, Wis., a corporation of Wisconsin

Application December 24, 1949, Serial No. 6,834

Term of patent 14 years

(Cl. D59—2)

To all whom it may concern:

Be it known that I, Wilbur J. Boucher, a citizen of the United States, residing at Green Bay, in the county of Brown and State of Wisconsin, have invented a new, original, and ornamental Design for a Paper Napkin, of which the following is a specification, reference being had to the accompanying drawing, forming part thereof.

In the drawing, the figure is a plan view of a quarter section of a paper napkin showing my design, the other quarter sections being substantially the same and arranged in proper relation to complete the napkin.

I claim:

The ornamental design for a paper napkin, substantially as shown and described.

WILBUR J. BOUCHER.
